UNITED STATES PATENT OFFICE

ALBERT H. ACKERMAN, OF CHICAGO, ILLINOIS, ASSIGNOR TO CATALYTIC CHEMICAL COMPANY, A CORPORATION OF COLORADO

PROCESS FOR TREATING MINERAL OILS

Application filed December 14, 1925, Serial No. 75,472. Renewed April 15, 1929.

My invention relates to processes of treating mineral oils and products containing carbon, particularly when in the form of hydrocarbons, and to the materials and methods of compounding the same for use in carrying out the processes.

The processes are particularly designed for the treatment of petroleum products in which is found carbon clustered or massed together so that the quality of the products may be affected or they may be of inferior grade, or which products may not be treated as efficiently as possible by the various refining processes employed and a more or less complete recovery of desired products made. My processes and materials are designed to be used with or without other treatments or processes, depending upon the materials treated, without affecting those processes except as it may improve the same, resulting in better products, increased yield, or in economy in the carrying out of present methods.

My invention has among its objects the production of suitable materials for carrying out my improved processes of treating hydrocarbons, and improved processes, and in such a manner that waste products may be recovered and be marketable. For example, the residuum from cracking plants, heretofore an expensive waste product, may be transformed into a valuable marketable product. It also has among its objects an improved process of treating what is known as lubricating oil stock from which lubricating oil is manufactured, or the treatment of cracking stock. It has also as an object an improved process for cleaning and keeping clean and unobstructed pipe lines in which waxes and the like accumulate, thereby tending to reduce the flow through the pipe line, as well as increase the cost of pumping. My invention has among its further objects the increasing of the efficiency for fuel oil by processing the same with treated petroleum coke, as will be more fully set forth hereinafter. Further objects and advantages and applications of my present invention will more particularly appear from the specific explanation of materials used and treatments followed, as well

as products treated, as will be hereinafter set forth and more particularly pointed out in the claims.

For a better understanding of the nature, scope and characteristic features of my present invention, reference may be had to the following description and the accompanying drawing which is a simple diagrammatic representation employed only for the purpose of illustration of a process for treating mineral oils or petroleum in order to procure therefrom the various products and by-products which are utilized in industry. It is to be understood that the diagram and the description pertaining thereto is illustrative only and solely for the purpose of explaining my invention and its application at various points in the processing of petroleum, for the procurement of the various petroleum products that are of commercial importance.

My invention is not to be limited to any specific method of treating petroleum in order to secure the commercial products therefrom, but is capable of broad application to different petroleum products in order to improve their quality and enhance their properties irrespective of the method employed in securing the petroleum products that I treat in accordance with my invention.

My invention can best be understood by first outlining briefly a method of processing petroleum in order to secure therefrom the various commercial products which I treat in order to purify them, recover them, or make them more acceptable, more efficient, or more marketable products.

To this end reference may be had to the accompanying drawing showing diagrammatically one process of treating crude petroleum to recover the by-products therefrom, the arrows in the drawing indicating various points where my present invention is applicable in treating the materials being processed, but it is to be understood that my invention is not to be limited solely to these points so indicated since my invention is applicable to a variety of points in the processing of crude petroleum.

To illustrate, the crude petroleum is drawn from the well and delivered, usually through

pipe lines, to a storage tank or tanks known as tank farms, from which the petroleum as required is fed to a still or other apparatus. From the still certain products are secured, among which may be enumerated the light hydrocarbons such as the naphthas, gasoline, burning oils, etc., which need not be enumerated in full. There is also obtained the distillate which forms cranking stock which passes to the crackers and lubricating stock which is employed in the manufacture of lubricating oil. The products obtained from the distillate by the cracking processes are for example, fixed gas, gasoline, kerosene, and the aromatic hydrocarbons, gasoline being the principal product and most desired. After the light hydrocarbons have been secured from the crackers, there remains a material known as the residuum, which has heretofore generally been a waste product. At the present time it is customary to provide dumps or earth reservoirs and carry out this waste product or residuum from the crackers and discharge it into these dumps, and it has been usually considered as a product without value, and so far as I know, prior to my method of treating, the same has been a total waste product in many instances. The refiners in many instances not only cross this off the books as a loss or waste, but in addition it is an expensive waste product as the same must be handled and transported far enough away from the refinery so as not to interfere with future operations or increase fire hazards, and obviously comparatively large areas are required for its storage, as well as the expense of constructing reservoirs for containing the same.

This material may vary in its consistency or viscosity, and generally it is a semi-solid material or heavy emulsion. I have found the same in many instances the consistency of a very firm jelly which may be often handled by shoveling as it is too thick to run or flow, and it consists of hydrocarbon clusters, some free carbon, and a percentage of other by-products, depending upon the base of oil or stock which was subjected to the cracking process. Immediately taken from the crackers, it, of course, does not contain water or moisture to any appreciable extent, although, of course, if it is old residuum in the dumps it may have accumulated some water from the weather.

After this material has been treated by my chemicals, the consistency of the material or its viscosity is such that it is more or less fluid and to such an extent that it may be barreled, pumped, or otherwise transported for commercial purposes. There is a considerable demand for the same at the refinery itself as it may be used as fuel oil in the operation of the plant, and it has been found by tests that the B.t.u. value has been increased over the usual fuel oil, and on the

market this reclaimed waste product may be and has been sold at a premium.

While I am aware that natural petroleum oils which are too viscous to be pumped or otherwise handled, and by reason of this have not been used as combustibles, for instance, in oil fed furnaces in which the fuel oil is pumped to the burners and atomized, have been treated or processed by the simple addition of naphthalene thereto without any further chemical or heat treatment in order to transform the oil into a free flowing fluid or to make it a more mobile liquid at ordinary temperatures so that it can be easily pumped, I am not aware that it has ever been proposed to treat or process residuum secured from oil crackers, which is known in the art as a waste product, in order to make it utilizable as a commercial product or to reclaim it as a viscous fuel oil possessing high B.t.u. value.

The part of the distillate from the stills known as lubricating stock, generally called stock, is treated in various ways for the purpose of securing lubricating oils as a petroleum product. Usually this is discharged into an agitator and treated with sulphuric acid during heating and agitation. From the agitator lubricating oil requiring further treatments and a residuum known as acid sludge are secured, which is at the present time a waste product. The acidulating and agitating process may be repeated at different times and need not be described in detail. In some instances it has been found that the lubricating stock is not adapted for the manufacture of lubricating oil, or that to treat the same so much sulphuric acid is required that the oil is ruined and without sufficient value for the desired purpose. By my treatment in connection therewith, it has been possible to obtain lubricating oil from lubricating stock where before the process was unsatisfactory, as for example, where the base product was from the Lost Soldier field, and in all instances it is possible to secure the lubricating oil with the use of less acid.

In connection with pipe lines, the crude petroleum may be pumped from the wells to the tank farms or tank farms to the stills. Where the distance from the well to the tank farm is very great, it is customary to have pumping and heating stations at intermediate points as the oil has a tendency to chill and its viscosity increase, causing a deposit of paraffine and other waxes and various products in the pipe lines so that, for example, a six inch pipe line might be so obstructed that it was only equivalent to a two inch pipe. In this instance it is necessary to clean the pipe lines, and in so far as I know, this has never been proposed in the manner in which I have proposed to do it. By the employment of my process and materials used in carrying out the process, not only is the

5 pipe line cleaned, but by the continued use of the materials the pipe line is maintained clean or unobstructed so that there is an immediate saving in pumping and heating expense, and initial equipment is reduced in cost as smaller size pipe lines may be employed.

10 My treatments or processes may be employed at other steps or points in the flow of the materials between the wells and the market, and has been, for example, found desirable and of value in treating cracking stock either as it comes from the crude stills and prior to entering the cracker, or during the 15 cracking process, as for example, after it has been subjected to heat in the furnace or heating coils and prior to its admission to the reaction chamber or while in the same or in similar or other apparatus employed in cracking processes.

20 My treatments or processes may likewise be employed for the treatment of petroleum coke which is generally considered as a waste product but by means of which I am able to 25 enrich fuel oil and increase the B. t. u. value to a very considerable extent.

25 By the employment of my processes and materials, all hydrocarbon clusters, regardless of the nature of the products in which 30 they may be found, whether in the hydrocarbons, that is, the lighter groups, or in the paraffine, residuum or the like, are broken down and in such a manner that there is no re-formation of the clusters, except as there 35 may be re-forming of clusters in the different products produced. In other words, the herein described difficulties have been overcome.

30 Referring now to the treatment of cracking still residuum which, as before stated, comprises hydrocarbon clusters of various kinds, some free carbon and percentages of other hydrocarbon products, depending upon the particular field from which the oil is taken, 45 as well as the various refinery processes through which the residuum has previously passed, I subject this residuum at the time of addition of the chemicals herein set forth to agitation, either compressed air jets or any 50 equivalent agitation, so as to cause a thorough chemical treatment of the entire mass of residuum.

55 The materials which I employ in the treatment of the residuum are anthracene, oil of mirbane, sulphuric acid, sodium hydroxide and naphthalene. In making up my composition of materials, while the same may be combined in various ways, I have secured satisfactory results and prefer to combine it in 60 substantially the manner and as follows:

10 lbs. anthracene, 4 lbs. oil mirbane, 2 lbs. sulphuric acid, 1 lb. sodium hydroxide. These ingredients are mixed together until a heavy paste is formed by first mixing the 65 anthracene with the sulphuric acid, and then

adding the oil of mirbane and then the sodium hydroxide, the same being permitted to stand in the open air for a period, generally for one hour. This mixture is then added to substantially 200 lbs. of flake naphthalene 70 and the whole ground in a ball mill for the desired time, two hours being generally the period for which I grind it. It appears that the treatment of the naphthalene in this manner prevents the naphthalene and also any of the other products in themselves from forming waxes or other products. In treating the residuum or the like, I usually treat the same in the proportion of 1 lb. of my mixture to approximately 8 bbls. of the residuum, agitating the residuum as previously mentioned. In some instances in the treatment of fuel oil residuum or other similar products the proportions may be varied, and I have found that in some cases only 1 lb. of the materials 75 need be used to 20 bbls. of the product to be treated.

80 The purpose of treating the anthracene with the sulfuric acid, as stated in the preceding paragraph, is to render the same more readily soluble in the oil products to be treated. The sulfuric acid appears to remove or destroy certain impurities in the anthracene. If, however, 85% pure anthracene is used in the composition, this sulfuric acid treatment becomes unnecessary. For reasons of expense, however, the common 40% green anthracene is preferred, and this requires the sulfuric acid treatment. The sodium hydroxide added later is for the purpose of removing or neutralizing any excess of sulfuric acid that might remain after the action of the latter on the anthracene, as the sulfuric acid, as such, is not needed in the final composition.

105 In its action the naphthalene acts as a cutter in separating the hydrocarbon clusters, the same to some extent acting like a miniature explosion, the action being observable when seen under a powerful microscope. 110 The anthracene when thoroughly co-mixed with the naphthalene, as is the case here, appears to slow up the action of the naphthalene and to a certain extent retard it so that it has sufficient time to perform its work or 115 function and thoroughly disintegrate the carbon clusters. The oil of mirbane decreases the fusing point of both the anthracene and naphthalene, sharpens their action, assists in preventing the formation 120 of the naphthalene wax and the like, and to some extent acts as a deodorizer. The sodium hydroxide facilitates the action on the clusters which may be enveloped in a moisture film. While naphtha might be 125 substituted for the oil of mirbane, it is not as satisfactory as it vaporizes more rapidly and does not attack the wax in the same manner or to the same extent as the oil of mirbane, nor tend to stop the wax from forming as 130

well. When I mention oil of mirbane herein, it is to be understood that naphtha may be substituted for it and that, for the purposes herein specified, is an equivalent of oil or mirbane.

5 It may be mentioned that in some instances where the material to be treated is a light oil residuum or the like, I have found that treatment with a composition of materials consisting of naphthalene, anthracene and sodium hydroxide greatly improves the residuum and enhances its value. However, it is generally preferred to treat the oil with the regular composition mixture previously set forth rather than with a modified one.

10 15 In the treatment of pipe lines to clean them or keep them clean, I apply my materials or mixtures to the crude stock as it comes from the well, although the same may be applied in the well or at various points in its flow, as will be hereinafter referred to. For this treatment, I prefer to use a combination of materials that will break up the carbon clusters, waxes, binders, fats, etc., so 20 that the petroleum remains more fluid and does not have a tendency to clog the lines. I have found a very satisfactory mixture to consist of flake naphthalene or a substitute, anthracene, a combination of alkali which I 25 prefer to make up with caustic soda, sodium phosphate, and ammonium carbonate, together with granulated sugar, a phosphate rock or powder or the equivalent, and a limited amount of sulfuric acid. For the phosphate rock, I have secured very satisfactory 30 results using a Florida phosphate rock or powder analyzing approximately as follows: carbon dioxide, silica, phosphorus, pentoxide, lime, alumina (including a trace of ferric 35 oxide as iron), magnesia, and fluorine. I 40 prefer the natural phosphate rock rather than a made-up combination of ingredients, and I find that slight variations in the 45 analysis of the rocks do not affect the treatments to any extent. As an illustration, I have secured satisfactory results by the use of 133 lbs. naphthalene, 21 lbs. anthracene, 58 lbs. caustic soda, 10 lbs. sodium phosphate, 10 lbs. ammonium carbonate, 20 lbs. granulated sugar, $\frac{1}{2}$ lb. sulphuric acid, 3 lbs. and phosphate rock. In mixing these, I take 50 first the caustic soda, sodium phosphate and ammonium carbonate, and mix the same with approximately an equal amount of the naphthalene, and grind the same thirty minutes in a ball mill, and then add the balance of naphthalene and the proper amounts of anthracene, sodium hydroxide, and phosphate rock, grinding the desired time, generally a 55 few minutes, say three to five minutes, and then add the granulated sugar and grind that for several minutes. See my copending application, Serial No. 168,819, filed as a division of my copending application, Serial No. 60 76,901, filed December 21st, 1925. The ma-

terial is then dumped and packed in air-tight metal drums for use.

When used, it is applied to the crude oil in a proportion of about 1 lb. to every 30 bbls. oil, the proportions depending on the particular oil to be treated, which is readily determined by testing. Where tank stock or residuum is treated, I treat in the proportion generally of 1 lb. to 15 bbls. of petroleum, and in instances where there is a very heavy 75 residuum substantially 1 lb. to 8 bbls., it being understood that these proportions may be varied within considerable ranges, this, as before mentioned, being determined by test.

In treating, the naphthalene, anthracene, oil of mirbane and sulphuric acid having more or less the same functions that they previously had in the materials previously described for the treatment of residuum from the crackers, it is impossible to state 80 exactly the chemical action due to the adding of the caustic soda, sodium phosphate or ammonium carbonate, but these apparently, when added to the petroleum from the well, produce an artificial heat by chemical action 85 and cooperate with the other chemicals in separating the hydrocarbon clusters, the same by chemical action increasing the temperature sufficiently to cause a permanent change 90 of the cold test range of the oils or large 95 bodies of hydrocarbons. These also work with the granulated sugar, it having been found after much experimenting that there was a chemical action creating more fluid substance. Of course, I know that in adding 100 the sugar, I have added a percentage of moisture in itself, and taking the alkalis referred to with the sugar, there is a catalytic action 105 on the hydrocarbon clusters, breaking them and making a more permanent fluid. Presumably the alkali addition breaks up the binders or cuts the binder the same as they would cut fats. By the attack that the combination makes on the binder that holds the 110 clusters together, together with the naphthalene and anthracene which has a milder effect on separating the clusters, the binder is destroyed so that the same is not formed again in the pipe lines or containers so far as the clusters in the paraffine wax, asphalt or tar. 115 The paraffine wax, tar or asphalt alone may be cut by the caustic soda, ammonium carbonate and granulated sugar mixture, without the presence of carbon in the wax as I have successfully demonstrated this, to-wit, 120 by adding the combination to crude oil where it has the presence of a large quantity of gasoline and different groups of oils of low specific gravities. I found that there was a cutting action on the paraffine or wax combination so that they would not adhere at 125 temperatures as low as 45° F., thereby indicating that the cold test is lowered.

The lubricating oil stock previously referred to is ordinarily a residuum which con- 130

sists of a heavy thick mass of hydrocarbons and waxes, depending on the base of the oil or the field from which it is taken, after the light ends, gases, oil and kerosene, etc., are distilled off at temperatures around 500 to 550° F. In order to make lubricating oil from this grade of material it is necessary to remove substantially all of the heavy ends of carbon and also the waxes, to extract the pure oil. When this is treated in the agitator with heat, agitation and by the addition of sulphuric acid, a violent chemical reaction takes place and the heavy carbons, or heavy residue of a carbon nature, is dropped to the bottom of the agitator. The thinner mass of fluid is on the top. The amount of acid required depends on the grade of lubricating stock treated, and this amount varies with whether it is the first or second, etc., treatment, or the particular base which may be used. It is considered dangerous to use an excess acid as it will stay in the thinner oil as the heavy carbons are dropped out, injuring the value of the oil for lubricating purposes.

My treatment is applied to the lubricating stock preferably at the time of discharge into the agitator or prior thereto, the same reacting as hereinafter set forth. I have found as a result of tests that a less amount of acid is required when my treatment is carried out, and I have found in some instances it is possible to make lubricating oil from some lubricating stocks where before it was impossible owing to the amount of acid required to get the break. Too much acid will cause so rapid a break as to clog the agitator in some instances. This was found true in the case of oil from Lost Soldier field previously referred to.

In treating or carrying out my process, however, I find that certain additional chemicals are desirable in order to produce a better product, although the product is improved by using either of the combinations previously mentioned. I have further found that the color may be improved by the addition of de-colorizers.

In the process of treating lubricating stock, I prefer to use the flake naphthalene, anthracene, caustic soda, sodium phosphate, ammonium carbonate, granulated sugar, phosphate rock, and in addition arsenious acid (white powder), arsenic sulfide (yellow powder), and golden antimony sulfide, these last three being particularly designed to improve the color. In making up a batch, the ingredients may be combined, for example, in approximately the following proportions, it being understood that the quantity required depends upon the amount of lubricating stock to be treated and that the proportions set forth are substantially approximate and may be varied within limits, depending upon the particular base from which the lubricating

stock was derived. I have secured satisfactory results when employing the materials in the proportion of 120 lbs. flake naphthalene, 100 lbs. phosphate rock, 35 lbs. caustic soda, 18 lbs. anthracene, 6½ lbs. ammonium carbonate, 6½ lbs. sodium phosphate, 15 lbs. granulated sugar, 1 lb. arsenious acid, 1 lb. arsenic sulfide, and 1 lb. golden antimony sulfide. This mixture is ground for an hour or more, and then there is added to the same 1 lb. more or less of oil of mirbane liquid.

In using the materials, I use ordinarily one-sixth pound per barrel of lubricating stock, but this may vary from a sixth or more down to a twelfth of a pound per barrel of lubricating stock, depending upon the particular kind of stock treated. After treatment thereafter in the usual manner, it is found that the heat and sulphuric acid treatment in the agitator is greatly improved. The chemicals cause a breaking up of the carbon clusters, and there is a better break between the sulphuric acid and the oil. There is a chemical reaction raising the temperature and breaking up the smaller hydrocarbon clusters that the acid would ordinarily not attack sufficiently to cause them to separate by gravity from the oil. The phosphate rock seems to greatly improve the action, causing the acid to break quicker and cut sharper with smaller quantities of acid and to bring a better color to the oil. Ordinarily the chemicals are put in about three to five minutes before the sulphuric acid is added, and it was found that the temperature immediately went up several degrees, and after the sulphuric acid was added there was a violent boiling created and the heavy sludge or heavy carbons formed immediately and dropped to the bottom of the agitator, leaving the light oil and waxes at the top.

As a result of this treatment, a very high grade of lubricating oil can be made from the Lost Soldier crude oil stock where before it was not possible to procure the same, owing to the amount of acid required. The sulphuric acid subsequent to the addition of my materials appears to make the attack or create the chemical action in a most satisfactory manner, presumably due to the fact that I have separated the hydrocarbon clusters before adding the acid, creating a more fluid substance and making it easier for the acid to attack the heavy carbons. In practice I have found that the result is apparent for when excess quantities of my materials are used, the sulphuric acid will work so fast the sludge will drop so quickly that it will clog the agitator and it is difficult to handle the same and transport it away from the agitator.

In employing my invention in the treatment of cracking-still stock, I prefer generally to use the same materials as used for the treatment of the stock in the pipe line previously referred to, except that the arsenious

acid, the arsenic sulfide and the golden antimony sulfide arsenic may be omitted, and as a matter of fact in some instances the phosphate rock or powder may also be omitted. Variations in the proportions of the ingredients may be modified to some extent, depending upon the nature of the materials to be treated. The cracking-still stock may be treated in the pipe lines before discharge 10 into the cracking-still or at some step in the cracking process. I have secured improved and satisfactory results, for illustration, in treating the oil in the expansion chamber or vaporizer or just prior to its discharge thereinto. As to the amount of my compound used in the above treatment, this may vary considerably, depending upon the particular materials to be treated or the previous treatments which it may have received prior to 20 passing to the cracker. I may mention, however, that I have secured very satisfactory results in employing one pound of the composition of materials to each ten barrels of petroleum product so treated.

25 While I have secured satisfactory results from the use of the same materials employed in treating the cracking-still residuum as previously described, I generally prefer the composition with the combination alkali and sodium hydroxide in this treatment more or less as used for cleaning pipe lines. It may be mentioned that this treatment, in so far as I am able to determine from tests that have been made, increases the efficiency of the 30 cracking process, and the residuum is improved, the same being more mobile and the clusters therein more thoroughly broken up so that in some instances the residuum may be used without further treatment or by 35 treatment with a greatly reduced quantity of my materials.

I have only mentioned a few of the possibilities of my treatments of breaking up the hydrocarbon clusters. The treatments, probably in some cases with necessary additions or modifications, may broadly be utilized for treating the hydrocarbons and breaking up hydrocarbon clusters at various stages in the refinery or other operations. I have 45 found that by grinding up petroleum coke, which is a hard coke substance, and adding, for example, my first materials mentioned as available on cracking-still residuum, during the operation of grinding, and then taking the entire mixture of chemicals with the dry pulverized petroleum coke and putting it back in the fuel oil, the fuel oil will dissolve a considerable percentage of the coke and increase the efficiency of the fuel 50 oil from thirty to thirty-five percent in energy heat or B. t. u. I am not aware that such treatment of petroleum coke has ever been considered before. I therefore wish to be understood as including by the term 55 cracking-still residuum any product which

contains carbon clusters which may be treated by my materials to reclaim the same in the manner herein set forth. The residuum from the crackers and the lubricating stock from the stills have been subjected more or less to the action of heat. In the residuum from the cracking-stills, the waxes have been substantially all destroyed, while in the lubricating stock only the waxes that have survived the temperature of the still remain. 70 In the pipe line stock coming from wells, storage tanks, none of the waxes or the like have been subjected to heat treatment other than the possible heat treatment used in sending it through the pipe lines at temperatures 75 comparatively low as compared with the temperatures of the stills or the cracking-stills. The composition of material for treating residuum then does not need to take into consideration to any material extent the treatment of waxes or the like which have been broken down in the previous heat treatments. 80 In lubricating oil or cracking stock, only those waxes that have survived the still need be treated with additional chemicals that are suitable to break them down in so far as possible. However, in the pipe lines, or crude oil from the well, all of the various waxes and fats, tars, asphalts, etc., as well as impurities, are in the crude oil. The composition 85 of materials for treating the crude oil must therefore perform an additional function or functions in more or less breaking down these waxes, fats or the like, so that the clusters therein may be treated. The 90 breaking down of the clusters in the pipe lines may not be complete, depending on the nature of the crude oil, its source, etc. Also in the various processes following, or in the 95 various refinery treatments, the carbons may re-cluster so that breaking down of clusters in the crude oil may not be permanent or sufficient for all of the later products.

As before mentioned, the employment of my compounds and processes at any step improves the efficiency of succeeding treatments or processes and apparatus so that even though I prefer to treat the petroleum in 100 succeeding refinery steps, the refining processes are improved by preceding treatments 105 so that there is a general improvement at all points between the crude in the well and the products to be marketed.

Having thus described my invention, it is 110 obvious that in view of the many varied conditions under which petroleums and their products are treated and the various processes and the varied apparatus employed in refining and treating them, as well as the varied characteristics of the petroleums and 115 their products, that considerable variation may be made from the above disclosure without departing from the spirit of my invention as set forth in the appended claims, 120 which should be construed accordingly. 130

What I claim as new and desire to secure by Letters Patent is:

1. A method of treating a petroleum product consisting in breaking up the carbon clusters therein by the addition of a composition resulting from admixture of suitable substances comprising naphthalene and sodium hydroxide, and agitating the said petroleum products by air jets.
- 10 2. The process of treating petroleum products which comprises subjecting the same to the action of a composition resulting from the admixture of materials comprising anthracene, sulfuric acid, oil of mirbane, sodium hydroxide and naphthalene.
- 15 3. The process of treating petroleum products which comprises subjecting the same to the action of a composition resulting from the admixture of material comprising substantially 10 parts anthracene, 2 parts sulfuric acid, 4 parts oil of mirbane, 1 part sodium hydroxide, and 200 parts naphthalene.
- 20 4. The process of treating petroleum products which comprises subjecting the same to the action of a composition resulting from the admixture of material comprising anthracene, sulfuric acid, sodium hydroxide, phosphate rock, naphthalene, sodium phosphate, ammonium carbonate and sugar.
- 25 5. The process of treating petroleum products which comprises subjecting the same to the action of a composition resulting from the admixture of materials comprising anthracene, sulfuric acid, sodium hydroxide, phosphate rock, naphthalene, sodium phosphate, ammonium carbonate, sugar, arsenious acid, arsenic sulfide and golden antimony sulfide.
- 30 40 6. The process of treating petroleum products which comprises subjecting the same to the action of a composition resulting from the admixture of materials comprising anthracene, oil of mirbane, sodium hydroxide and naphthalene.
- 45 7. The process of treating petroleum products which comprises subjecting the same to the action of a composition resulting from the admixture of materials comprising anthracene, oil of mirbane, sodium hydroxide and a hydrocarbon of substantially the same specific gravity and fusing range as naphthalene.

In testimony whereof, I have hereunto signed my name.

ALBERT H. ACKERMAN.
